REFRIGERATOR CAR CONSTRUCTION

Kurt E. Zeidler, Pittsburgh, Pa., assignor to
Standard Railway Refrigerator Company, Chi-
cago, Ill., a corporation of Delaware

Application April 24, 1939, Serial No. 269,649

6 Claims. (Cl. 62—17)

My invention relates to improvements in refrigerator cars for transporting perishables, such as fish, meat, fruit, vegetables, etc., but more especially to the so-called top bunker type.

One of the objects of my improved construction is to provide stiffening means in the metallic top of a refrigerant container.

Another object is to provide ducts for the circulation of air over the top of a refrigerant container.

Another object is to utilize the refrigerant container to support the insulating materials of the car roof.

Other objects and advantages will be apparent from the following description and the accompanying drawing.

In the drawing:

Fig. 1 is a half cross section of a railway refrigerator car showing a refrigerating unit incorporating a refrigerant container having my improved construction. The opposite half of the car which is not shown is understood to be of identical construction.

Fig. 2 is a longitudinal vertical cross section through the refrigerating unit, taken as indicated by the line 2—2 in Fig. 1.

My invention is adaptable to a refrigerator car having spaced apart insulated car walls 2, an insulated roof 3, an insulated floor 4, a foraminous floor or floor rack 5 above the insulated floor and an air space 6 between said floors.

A refrigerant container 8 is positioned under the roof 3 of the car and adjacent the side wall 2 of the car. The container 8 is provided with a top 9 having corrugations 10 formed therein and extending substantially from edge to edge of the top 9. The container top 9 fits snugly against the underside of the roof 3 and to prevent the roof insulating material 11 from filling the space 12 between the corrugations 10, means 13 is provided. This means 13 may consist of chicken wire, wire mesh, expanded metal, plywood, masonite or any other suitable means that will prevent the roof insulation 11 from settling into the spaces 12. Since the corrugations 10 extend from side to side of the top 9, the spaces 12 form flues for the movement of air over portions of the top 9.

The refrigerant container 8 is preferably spaced away from the adjacent wall 2 to provide an air flue 14 therebetween. A hatch opening 15 is provided preferably in the roof of the car above the refrigerant container 8 for filling it with a refrigerant, removing the refrigerant or cleaning the container. The hatch opening may be pro-

vided with the usual plug, lid, locking and supporting mechanisms. Refrigerant containers are preferably arranged in a row adjacent the eave of the car and are spaced apart 16 to provide air flues between the ends of the respective containers. In this arrangement the bottom, ends, sides and portions of the top form cooling areas for the circulating air.

An insulated partition 18 is preferably provided on the inside of each side wall 2 and spaced apart therefrom to provide a vertical wall flue 20 which communicates with the air space 6 below the foraminous floor 5 and also communicates with the air flue 14 having contact with the refrigerant container.

Under certain conditions frost will form on the bottom 17 of the container. To prevent melted frost from dripping on the lading an insulated partition 18 is provided below the container 8. This insulated partition 18 is spaced apart from the container 8 so as to provide an air flue 21 therebetween which communicates with the vertical air flue 20 near or in the side wall of the car. The partition 18 is preferably inclined outwardly and downwardly (see Fig. 1) so that air cooled and densified by the refrigerant will move by gravity into the vertical flue 20.

The insulated partitions 18 on the opposite side of the car are spaced apart to provide an air passageway 22 adjacent the longitudinal center of the car through which the warm air rises and moves into the refrigerant chambers on opposite sides of the car. The margins of the inclined partitions 18 adjacent the passageway 22 may be provided with insulated members 23 extending upwardly therefrom so as to further raise the bottom of the air entrance parts into the refrigerant chamber above the lower portion of the inclined partition 18 thereby cooperating with the inclined partition to direct the movement of circulation of air. The members 23 are spaced away from the container 8 to provide a flue 24.

The circulation of the air in the car I have described will be substantially as follows: Air warmed by the lading will rise and striking the underside of the inclined partition 18 will be directed into the passageway 22 and enter the refrigerating chamber. Here contacting the refrigerant container the air will be cooled and densified and a portion of the air will flow through the flues over the top of the refrigerant container and into the flue 14, the remainder of the air entering the chamber upon being cooled and densified will flow through flue 24 and into flue 21 under the container. By gravity the

densified air in flues 14 and 21 will descend the vertical flue 20 thence entering the space 6 under the foraminous floor 5 from whence it will rise to replace the warmed air.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having spaced apart insulated car walls, a roof insulated by pliable insulation, an insulated floor, a foraminous floor spaced above the insulated floor cooperating to form an air space between said floors, a refrigerating compartment under said roof and adjacent one of said walls, and means providing for the flow of air into said compartment, a vertical flue associated with said wall, said flue extending substantially from near the floor to near the refrigerating compartment and communicating at the lower portion thereof with said space and at the upper portion thereof with said refrigerating compartment, the combination of a refrigerant container positioned within said compartment, said container arranged and associated with said roof to provide a support for the pliable insulation thereof, the top of said container having offset portions formed therein projecting away from the container and extending substantially from side to side of said top to stiffen said top, and means to prevent said pliable insulation from entering the spaces between said offset portions, thereby forming a series of ducts above the portions of said top between the offset portions so that air warmed by the lading rising upwardly enters the refrigerating compartment and passing through said ducts is cooled and densified and therefore moves down the vertical flues by gravity into the space below the foraminous floor from whence it rises to replace the warmed air.

2. In a refrigerator car having spaced apart insulated car walls, a roof insulated by pliable insulation, an insulated floor, a foraminous floor spaced above the insulated floor cooperating to form an air space between said floors, a refrigerating compartment under said roof and adjacent one of said walls, and means providing for the flow of air into said compartment, the combination of a refrigerant container positioned within said compartment, said container arranged and associated with said roof to provide a support for the pliable insulation thereof, the top of said container comprising portions arranged in spaced substantially horizontal planes which are connected by webs, and means to prevent said pliable insulation from entering the spaces above the lower of said planes, thereby forming a series of ducts for the circulation of air between said roof insulation and the portions

in the lower of said planes, said last mentioned means comprising foraminous material interposed between said container top and said roof insulation.

3. In a refrigerator car having spaced apart insulated car walls, a roof insulated by pliable insulation, an insulated floor, a foraminous floor spaced above the insulated floor cooperating to form an air space between said floors, a refrigerating compartment under said roof and adjacent one of said walls, and means providing for the flow of air into said compartment, the combination of a refrigerant container positioned within said compartment, said container arranged and associated with said roof to provide a support for the insulation thereof, the top of said container having offset portions formed therein projecting away from the container and extending substantially from side to side of said top, and means to prevent said pliable roof insulation from entering the spaces between said offset portions, thereby forming a series of ducts for the circulation of air above the portions of said top between said offset portions, said last mentioned means comprising foraminous material interposed between said container top and said roof insulation.

4. In a refrigerator car having a roof comprising pliable insulation, a refrigerant container below said roof, said container having a top formed with corrugations projecting alternately upwardly and downwardly, said insulation supported by the upwardly projecting corrugations to form ducts between said insulation and the downwardly projecting corrugations, foraminous material arranged to support the pliable insulation substantially clear of said ducts, and means to direct a flow of air through said ducts.

5. In a refrigerator car having a roof comprising pliable insulation, a refrigerant container below said roof, a top on said container, means associated with said top to support said insulation in spaced relation to certain parts of said top to form ducts between said insulation and said parts of the top, foraminous material arranged to support the pliable insulation substantially clear of said ducts, and means to direct a flow of air through said ducts.

6. In a refrigerator car having a roof comprising pliable insulation, a refrigerant container below said roof, a top on said container, means associated with said top to support said insulation in spaced relation to certain parts of said top to form ducts between said insulation and said parts of the top, said ducts arranged to extend between opposite sides of said container, foraminous material arranged to support the pliable insulation substantially clear of said ducts, and means to direct a flow of air through said ducts.

KURT E. ZEIDLER.
